INTRAMEDULLARY NAIL

John Bambara, Bloomfield, and Michael T. Modny, Glen Ridge, N. J.

Application December 17, 1952, Serial No. 326,556

3 Claims. (Cl. 128—92)

1

Our invention relates generally to nails used in bone surgery and specifically to intramedullary nails having provision for manipulation after insertion in a bone cavity.

It is among the objects of our invention to provide an intramedullary nail which is easy to insert.

It is a further object of our invention to provide an intramedullary nail which may be inserted into the broken end of a bone and manipulated through a single window cut in the bone; it does not require supplemental or additional windows for its insertion, and when it is in place, it is wholly within the bone and no portion of its protrudes therefrom.

It is yet a further object of our invention to provide an intramedullary nail which does not migrate, but remains fixed in place.

It is yet another object of our invention to provide an intramedullary nail which may be manipulated through a single window until it assumes its proper place in the bone.

These objects and advantages, as well as other objects and advantages, may be achieved by the device illustrated in the appended drawings, in which:

Figure 1 is a view in perspective of a part of our intramedullary nail;

Figure 2 is an end view thereof;

Figure 3 is a side view thereof;

Figure 4 is an edge view thereof;

Figure 5 is a view of a broken bone with our intramedullary nail in the first stage of insertion through the broken end of one part of the bone;

Figure 6 is a view showing our intramedullary nail completely swallowed by one part of the broken bone and with the other part of the bone in alignment to receive the nail; and

Figure 7 is a view showing our intramedullary nail moved into its final position extending substantially equally into the bone at each side of the break.

In the treatment of broken bones it has in the past been the practice in some instances to bring the bones into alignment through the use of a nail inserted into the soft center of the bone. Such insertion usually takes place by drilling a hole in the end of the bone and forcing the nail into the interior bone until it extends beyond the point of break and one either side of it. In forcing the nail into the bone in this manner, it is frequently found a difficult thing to cause the entry of the nail into the bone. Furthermore, an incision may be made near the point of the break to control the proper entry of the nail into the other portion of the bone and to insure perfect

2

alignment. Thus, two incisions may be necessary. Since nails are frequently disposed with their ends only a short distance away from the end of the bone, a movement of the nail may cause a migration or extrusion of the nail beyond the end of the bone, and it may actually be extruded through the flesh.

We have discovered that it is possible to devise a nail which may be inserted through the broken end of the bone and manipulated through a single incision; such an insertion may be easily accomplished; the nail may be easily manipulated into place; once in place it will not migrate; and further only a rather small nail is usually necessary.

Referring now to the drawings in detail, it will be seen that our nail consists of a rod-shaped body member 11 having a plurality of fins 12 extending therefrom. The exact number of fins may be a matter of choice. In the preferred form, shown in Figures 1 to 4 inclusive, however, four fins extend from the rod. The nail, therefore, is cruciform in cross-section. It is preferred that the fins 12 be disposed at an angle of 90 degrees to each other. Transverse to the longitudinal axis of the nail and perpendicular to that axis, a plurality of holes 13 at regular intervals are bored through the rod 11. These holes are perpendicular to the central axis of the rod member and coaxial with a line bisecting the angle between the adjacent ribs.

The use of our nail is illustrated in Figures 5 to 7. A broken bone 17, 18 is presented. If there is comminution, the extra pieces may be secured to the main portion of the bone by screws. The next step in preparing the bone for the use of our nail is fenestration. Immediately adjacent to the broken end of the bone, a small window 19 is bored or cut into the center of the bone. The center of the bone 17, 18 may be of soft consistency and have a cavity of such dimensions that it will readily receive our nail. However, if this is not the case, then the center of the bone may be reamed to such a degree as to receive our nail 11. When this has been done, then the nail 11 is inserted into the center of the bone until it is completely encompassed by the bone 17, 18. This may be done by applying pressure to the end of the nail 11 to drive it all the way in; or by exerting leverage on the nail through the window 19 by inserting the lever 20 through the window 19 cut in the bone 17, 18 and engaging it with the holes 13, 13 successively in the nail. Thus by using the edge of the window 19 as a fulcrum for the lever 20, the nail may be manipulated into and completely swallowed by one end 17 of the bone and caused to enter it entirely. Thereupon, the other broken end

18 of the bone is brought into precise alignment with the first end 17 of the bone into which the nail has been inserted. Then the lever 20 is inserted into the window 19 in the bone 17, 18 and by using the edge of the window 19 as a fulcrum, the nail 11 is caused to advance from one end 17 into the other end 18 of the bone. When, by the action of the lever, the nail has been advanced to such position that it is approximately equally extensive into both ends of the bone 17, 18, it may be locked in this position by causing a screw to penetrate the bone and into one of the holes in the nail. The fins 12 have passed through the soft, spongy marrow in the center of the bone and engage the more dense outer walls of the bone. Rotation of the fragments of the bone is thereby prevented. The operation is then complete and the incision in the flesh may be closed in the usual manner.

It will be seen that by following our procedure, and using our nail 11, 14 it is only necessary to make a single incision at the point where the bone is broken. The reaming of the center of the bone and the cutting of the window 19 in the bone may be simply accomplished through this single incision. It is also easy to insert our nail through the single incision and to manipulate it both into and out of the bone by the lever 20. Since the joint end of the bone has not been cut open for the purpose of admitting a nail 11, 14, there can be no migration of our nail. Furthermore, the holes permit of the locking of the intramedullary nail in place by a screw so that no movement whatsoever of the nail is possible. In addition to that, our intramedullary nail may be much smaller than the conventional intramedullary nail which is merely a piece of metal with arcuate cross-section.

The foregoing description is merely intended to illustrate an embodiment of the invention. The

component parts have been shown and described. They each may have substitutes which may perform a substantially similar function; such substitutes may be known as proper substitutes for the said components and may have actually been known or invented before the present invention; these substitutes are contemplated as being within the scope of the appended claims, although they are not specifically catalogued herein.

10 We claim:

1. An intramedullary nail comprising a rod-shaped member having a substantially cruciform cross section and with a plurality of transverse passages therein.
- 15 2. An intramedullary nail comprising a rod-shaped member having a substantially cruciform cross section and with a plurality of transverse passages extending therethrough transverse to the longitudinal axis of the member.
- 20 3. An intramedullary nail comprising a rod-shaped member having a substantially cruciform cross section and with a plurality of transverse passages extending therethrough equidistant from each other and transverse to the longitudinal axis of the member.
